UNITED STATES PATENT OFFICE.

ALBERT BALDWIN WOOD, OF NEW ORLEANS, LOUISIANA.

REVERSIBLE PUMP.

Application filed July 6, 1925. Serial No. 41,613.

This invention relates to fluid pumps and has for one of its primary objects the provision of a pump of simple construction which will pump at full efficiency in either direction by merely rearranging some of the parts thereof.

Another object of my invention is the provision of a pump, the casing of which is so constructed that one portion may be detached for exposure and/or removal of the pumping elements, while the remaining portion serves as a stay to the pipe line.

A further object resides in the novel arrangement and construction of parts herein-after more fully pointed out.

How the foregoing, together with such other objects and advantages as may hereinafter appear, or are incident to my invention, are realized, is illustrated in preferred form in the accompanying drawings, wherein—

Fig. 1 is a sectional side elevation of a pump embodying my improvements;

Fig. 2 is a view similar to Fig. 1 but with the reversible parts shown in reversed position;

Fig. 3 is a cross section taken on the line 3—3 of Fig. 1;

Fig. 4 is a longitudinal section of the pumping elements removed from the casing, and

Fig. 5 is a longitudinal section of the case assembled with the pumping elements removed.

Referring now to Figure 1, it will be seen that the arrangement of parts is such that the flow of the fluid is from the left to the right and that the pump comprises in general the casing A, and the pumping elements B which are constructed and arranged to be handable as a unit, such unit being clearly shown in Fig. 4.

The casing A is of elbow like form and is divided into three sections, 5 being an elbow member normally constituting the inlet portion of the pump, 6 a similar member normally constituting the outlet portion, and 7 a tubular intermediate member for connecting the members 5 and 6. The casing is longitudinally split in its general plane as indicated at 8 so that a portion thereof, in this instance the upper portion, may be removed to give access to the pumping elements B, the removable portion constituting in effect a cover formed of a portion of the elbow members and the intermediate member.

The members referred to are provided with flanges suitable for securing them together and to the pipe line 9. The cover portion may be detachably secured to the lower portion of the casing in any suitable manner.

Thus it will be seen by this arrangement that the cover may be detached to expose and/or to remove the pumping unit without disturbing the pipe line; in other words the remaining or lower portion of the casing serves as a stay for the line. If desirable the cover portion may be attached to the lower portion and caps 21 secured thereto covering the opening for the shaft, as shown in Fig. 5, thus providing a continuous pipe like connection for the line thru which fluid may freely pass, there being no interference with the pumping elements.

Reverting now to the pumping unit, 10 indicates the propeller shaft having bearings 11 carried by the casing, 12 the propeller, 13 a reversible lining for the casing A and 14 and 15 guiding and deflecting cones respectively, said lining 13 and the cones 14 and 15 defining the inlet and delivery chambers of the pump. The lining 13 is here shown as made in two sections, the section 16 adjacent the impeller being readily replaceable as wear takes place, and the lining as a whole being supported by the casing A and complementary thereto in either end to position. To this end the lining is provided with flanges 17 of different depths adapted to register with the supporting surfaces 18 on the interior of the casing, such flanges and surfaces being complementary in either end to position of the lining. The cones 14 and 15 are carried by the casing in any suitable manner.

Diffusion vanes 19 may be provided if desirable.

Referring to Fig. 2, it will be seen that the impeller elements B, including the lining 13 has been reversed end for end so that by merely reversing the direction of rotation of the shaft 10 the pump will deliver in the opposite direction, the elbow member 6, of course, becoming the inlet and the member 5 the outlet. In this connection, it is to be noted that the impeller is so located on the shaft as to register properly with the lining 13 in its reversed position and that the cover of the casing is symmetrical about its vertical centre line so that it may be replaced in either end to position producing the same inlet and delivery chambers as in Fig. 1;

whereby the pump functions equally well in either direction.

Suitable couplings 20—20 are provided at either end of the impeller shaft and exterior of the casing for connection to a driving mechanism, these couplings being so spaced that driving connection can be made between either end and a fixed motor or other source of power.

10 From the foregoing it will be seen that by reversing the parts as described the flow of the fluid may be reversed, the pump operating at full efficiency in either direction, which result cannot be attained with pump impellers designed to pump in either direction by merely reversing the rotation of the pump.

By my invention I can use a screw pump and secure full efficiency in either direction 20 of rotation.

What I claim is:

1. A reversible pump including pumping elements reversible end for end, and a casing for said elements symmetrical to each 25 side of its vertical centre line and split in a direction longitudinally of the axis of said elements, whereby said pumping elements may be reversed end for end therein.

2. A reversible pump including pumping 30 elements, reversible end for end, and a casing for said elements symmetrical to each side of its vertical centre line, whereby said pumping elements may be reversed end for end therein, the casing having like inlet and 35 discharge members and the pumping elements including a casing like member formed to provide a proper delivery chamber for the pump.

3. In a reversible pump, the combination 40 of a casing; a pumping unit comprising a shaft, guiding and deflecting cones, an impeller, and a deflecting and guiding liner; and supporting means for said pumping unit on said casing, the casing and pumping 45 unit being complementary for support of the unit when the latter is reversed end for end.

4. A reversible pump comprising in combination a casing having a fluid inlet and a fluid delivery outlet; a lining for said casing 50 formed to deflect and guide the fluid and reversible end for end; an impeller shaft; and an impeller reversible end for end with its shaft, said impeller being so disposed on its shaft to have the same relation to the lining 55 when said parts are in normal or in reversed positions.

5. A reversible pump comprising in combination a horizontally split casing having a fluid inlet and a fluid delivery outlet, the 60 upper portion of which is reversible end for end, an impeller and impeller shaft having its bearing in said casing and being reversible end for end, an end for end reversible fluid deflecting and guiding lining for said 65 casing, and supporting means for said lin-

ing, all of said reversible elements being complementary to their associated elements in end for end positions.

6. A reversible pump comprising a pair of spaced elbow members, each of which is 70 adapted to constitute either the inlet or the discharge of the pump depending on the direction of flow; an intermediate casing uniting the two; a pump shaft and pump runner and pump casing constituting a unit hand- 75 able as such; said elbows each having similar bearing means whereby said unit may be reversed end for end; the elbows and the intermediate casing being split in a direction lengthwise of the pump shaft, whereby 80 said unit may be inserted or removed; said pump casing being supported from said intermediate casing and said two casings being complementary for support of the pump casing 85 when the latter is reversed end for end.

7. In combination a pipe line having a section thereof formed of a pair of spaced elbow members and an intermediate member uniting the two, said section being split in the general plane thereof; and pumping 90 elements insertable in and removable from said section upon removal of one portion of the section, the remaining portion serving to stay the pipe line and the removed portion of the section upon being replaced with 95 the pumping elements removed serving to provide a noninterrupted connection for the line.

8. In combination a pipe line having a section thereof formed of a pair of spaced elbow members and an intermediate member uniting the two, said section being split in the general plane thereof; and pumping elements insertable in and removable from said 100 section upon removal of one portion of the section, the remaining portion serving to stay the pipe line, and said elbow members having detachable bearing means for the 105 pumping elements.

9. In combination a pipe line having a 110 section thereof formed of a pair of spaced elbow members and an intermediate member uniting the two; pumping elements hand- 115 able as a unit insertable in and removable from said section, the section being so split that one portion constitutes a cover and the other a stay for the line; and detachable bearing means for said pumping elements.

10. In combination a pipe line having a section thereof formed of a pair of spaced elbow members and an intermediate member uniting the two, said section being split in the general plane thereof; and pumping elements hand- 120 able as a unit insertable in and removable from said section upon removal of one portion of the section, the remaining portion serving to stay the pipe line, together with means for attaching said section to the pipe line.

11. In combination a pipe line having a 125

section thereof formed of a pair of spaced elbow members and an intermediate member uniting the two, said section being split in the general plane thereof; and pumping elements handable as a unit insertable in and removable from said section upon removal of one portion of the section, the remaining portion serving to stay the pipe line, together with driving means for said pumping elements exterior of said section.

12. In combination a pipe line and a pump in said line, including pumping elements re-

versible end for end and a casing for said elements symmetrical to each side of its vertical centre line, whereby said pumping elements may be reversed end for end therein, said casing being split for removal of a portion thereof to expose the pumping elements for purposes of reversal and the remaining portion of the casing serving to support the pumping elements and to stay the pipe line.

ALBERT BALDWIN WOOD.
